UNITED STATES PATENT OFFICE.

GEORGE W. BROWN, OF GALESBURG, ILLINOIS.

CORN-PLANTER CHECK-ROWER.

SPECIFICATION forming part of Letters Patent No. 258,217, dated May 23, 1882.

Application filed January 21, 1882. (Model.)

To all whom it may concern:

Be it known that I, GEORGE W. BROWN, a citizen of the United States, residing at Galesburg, in the county of Knox and State of Illinois, have invented certain new and useful Improvements in Corn-Planter Check-Rowers, of which the following is a specification, reference being had therein to the accompanying drawings.

10 This invention relates to improvements in corn-planter check-rowers of that class in which a stretched wire with tappets is used to impart movements to the seed-slides; and it consists in constructions and combinations hereinafter described and claimed.

15 In the accompanying drawings, which illustrate my invention, Figure 1 is a top plan. Fig. 2 is a top plan. Fig. 3 is a top plan. Fig. 4 is a sectional elevation in the line xx in Fig. 2. Fig. 5 is a plan of the tappet-wire and a tappet secured thereto. Fig. 6 is a plan of the tappet-wire and sectional plan of the tappet secured thereto. Fig. 7 is a central section of a tappet-ball. Figs. 1, 2, and 3 of the drawings show the working parts in different relative positions.

20 Referring to the drawings by letters, letter A represents a case with its cap or cover removed to expose to view the main working parts of my invention.

25 B is a head hinged or journaled to the bottom of the case A, and its outer end, b, extended beyond the case for attachment of a rod or other device to transmit movement to the seed-slides from the oscillations of the head B. Arms C C' are hinged to the head B and extend from one side thereof, and arms D D' are hinged thereto and extend from its other side. Each arm C C' has a lug, c, at its free end, 30 which projects laterally and outwardly therefrom, and each arm D D' has a similar lug, d. The arms C C' are straight from near their mid-lengths to their free ends, and the arms D D' are the same. A standard or guide, E, projects upwardly from the bottom of the case A between the arms C C', and another, E', between the arms D D'. As the head B is oscillated the free ends of the arms C C' and D D' are kept in straight paths by means of their 35 respective side lugs sliding in contact with the side walls of the case A and their adjacent

sides sliding against the standards between them.

The parts hereinbefore described by letters are substantially the same as shown in an application for patent which I have made, even date herewith, and as they are claimed in said application I do not claim them here.

40 The case A may be fixed upon the planter in any desired manner, whereby the push-bars F F', which enter the ends of the case A, may be given a reciprocating motion by means of any desired or known connection with the forked levers on which the tappets on the stretched tappet-wire act.

45 G G' are cam-track bars, hinged one to each side of and near the end of the case A, duplicates of which, H H', are hinged to the other end of the case. Each track-bar G G' is hinged at one end to the side wall of the case A a short 50 distance above the bottom of the case, and the end of the track-bars toward the head B are pointed and rest on the bottom of the case, as shown by dotted lines at Fig. 4.

55 The parts being in relative positions as shown at Fig. 1, the push-bar F, advancing, will force the arm C backward beneath the cam-track G, which swings upwardly as the lug c on the arm C comes beneath it, and thus permits the arm C to slide forward without 60 rising, as shown by full lines at Fig. 2. When the push-bar F has reached the end of its throw, as shown at Fig. 3, the end of the arm C will have passed from beneath the cam-track G, which cam-track will then fall to the 65 position shown by dotted lines at Fig. 4. As the arm C is thrust forward, as last described, the arm C' will be thrust backward by the bar B, and its lug c will slide up the cam-track G', and thus elevate the end of the arm C', so that 70 the push-bar F may slide forward beneath it, as shown at Figs. 2 and 3. When the push-bar F is then retracted or slid backward it will not act on either arm C or C', except to 75 allow the arm C' to drop to the bottom of the case A as it passes from beneath said arm. At the next forward movement of the push-bar F it will act upon the arm C' and force it 80 forward to pass beneath the cam-track G' and the arm C backward to be elevated by the 85 cam-track G and permit the push-bar to pass beneath the arm C, and so on continuously,

giving movement to the bar B and to the seed slides. The arms D D' are duplicates of the arms C C', and are acted upon in the same manner by the push-plate when it is operated at that end of the case A.

The tappets are secured to the tappet-wire as follows: Each spherical tappet I is formed with a cavity, *i*, in one side, and a hole, *i'*, extending from the bottom of said cavity through said tappet. The wire J is formed in sections united at each tappet. The end of one section is bent back to form an eye, *j*, and the ends of this section are then passed through the hole *i'*, so that the eye *j* rests in the cavity *i*, as shown, where it is securely held by coiling the end of the wire upon itself, as shown at Fig. 6. An eye, *k*, on the end of another section of wire is then interlocked with the eye *j*, and held thereto by coiling its end upon itself, as shown. Knots secured to the wire in the foregoing manner are not only cheaply and easily made, but are firmly held in place and permit bending the wire, as shown by dotted lines at Fig. 5, sufficiently for readily winding it upon the spool, but not in a manner to allow "kinks" to form in the wire when slack.

What I claim as new is—

1. In a check-rower, in combination with the head B and sliding arms C C', the hinged cam-tracks G G', adapted to swing upwardly to allow the arms C C' to pass back below them, and to fall to form inclines up which the same

arms slide to elevate them, substantially as and for the purpose specified.

2. In combination with the head B, with arms C C' hinged thereto, and push-bar F, adapted to act alternately on said arms C C', the hinged cam-track bars G G', adapted to swing upwardly to allow the arms C C' to pass beneath them, and to fall to form inclines for elevating said arms, substantially as and for the purpose specified.

3. In combination with the head B, having arms C C' hinged thereto, with lugs *e* on their free ends, the cam-tracks G G', adapted to swing to permit said lugs *e* to pass beneath them, and to form inclines up which said lugs *e* slide to raise the arms C C', substantially as and for the purpose specified.

4. A tappet-wire formed of tappets with a cavity in one side, which forms a seat for an eye on one section of the wire, which eye is held in the tappet, substantially as herein described, and interlocked with an eye on the adjacent section of the wire, which eye is held by coiling the wire, substantially as and for the purpose specified.

In testimony whereof I affix my signature in presence of two witnesses.

GEORGE W. BROWN.
